NEAL T. MCKEE, OF BRONXVILLE, NEW YORK, ASSIGNOR TO GENERAL STEEL CASTINGS CORPORATION, OF GRANITE CITY, ILLINOIS, A CORPORATION OF DELAWARE

LOCOMOTIVE BOILER

Application filed June 15, 1929. Serial No. 371,155.

This invention relates to locomotive boilers and more particularly to the so-called mud-rings in fire boxes of the ordinary stayed water leg type. The object of the invention is to provide a more satisfactory mud-ring for this purpose which will not be subject to some of the disadvantages of those at present in use.

The invention is illustrated in the drawings herewith, in which drawings Fig. 1 represents a central, longitudinal, vertical section through a locomotive fire-box with my invention in place; Fig. 2 is a section on line 2-2 of Fig. 1; Fig. 3 is an enlarged section on line 3-3 of Fig. 2; Fig. 4 is a section on line 4-4 of Fig. 3; Figs. 5 and 6 are sections corresponding respectively to Figs. 3 and 4 illustrating a modification.

Referring to Fig. 1, the fire-box comprises an outer sheet 1, inner sheet 2, back head 3, back sheet 4 and throat sheets 5, all of the usual or any preferred construction. In practice these are suitably stayed. The legs each comprise an outer sheet 6 and an inner sheet 7 between which is placed the rectangular mud-ring, the sheets and the mud-ring being riveted together. In the ordinary practice, the mud-ring is a solid piece. Impurities precipitated in the water gradually collect in the lower parts of the water legs, accumulating on the mud-ring until the locomotive is washed out when this sludge is removed, being carried out by the wash-out water. While the sludge is present, however, it interferes with the free heat transfer from the inner sheets to the water in the water legs, and by doing so endangers the metal of the inner sheets of these legs at these points. The fire is immediately adjacent to the endangered points in the ordinary construction, the grates being so located that the fuel bed on them is directly opposite the endangered areas.

My invention contemplates a mud-ring which has a space provided in which the sludge will accumulate instead of lying in contact with the heated sheets, said space preferably being below the fire level. The sheets are secured to the ring by means of the rivets 8 and the ring extends below the lower edges 9 of the sheet, said portion ex-

tending below the edges having a hollow interior as shown at 10. This interior cavity preferably extends clear through the entire body of the mud-ring. It is connected to the upper surface of the mud-ring by a series of ducts 11. The bottom of the ring is preferably provided with a plurality of normally plugged cleaning apertures 12. Valved connections 13-13 are also preferably provided at the corners, as indicated, for blow-off purposes.

At 14 is indicated the grate showing the level at which the upper surface of the grate is located.

In operation sludge and slime collecting in the water legs will find its way through the ducts 11 into the chamber or cavity 10. The space in the water legs opposite to the heated areas of the inner sheets will remain substantially free from sludge and the danger of their being injured by excessive heating is thereby minimized. The ducts 11 are preferably so arranged that their upper ends are adjacent to the inner tube sheet so that the removal of sludge is most effective adjacent to this sheet. When the locomotive is washed out, the current water circulating downward through the ducts 11 and out through the wash-out plugs 12 and cocks 13 will thoroughly clean out all accumulations in the water legs and in the cavity 10. Whereas with the ordinary system of construction, where there are blow-off and wash-out plugs at the corners only, the mud and sludge are apt to be removed only from points adjacent to these openings, the ducts 11 of my construction cause such sludge to be drawn from points all along the bottom of the water-legs as the boiler is blown off.

In the form of Figs. 5 and 6 the sheets 6 and 7 extend down to the lower surface of the mud ring and the chamber 10 is raised sufficiently to permit the use of two rows of rivets 8 below the cavity 10. A further row of rivets 8' is used through the portion of the mud-ring above this cavity. Suitable connections for the removal of the sludge from the chamber 10 in this case are provided through the sheet 6 and the vertical adjacent wall of the chamber 10. The grate in this case is 100

also so arranged that its upper surface does not lie below the upper surface of the mud-ring. The sludge accumulating in chamber 10 leaves the space adjacent to the sheet 7 clean so that the water in the water leg can again get into intimate contact with them and thus protect the sheets.

It is obvious that variations will in practice occur from the specific form illustrated and described herein but still within the scope of 10 the spirit of the invention and of the appended claims.

I claim:

1. In apparatus of the class described comprising a fire box with the usual water-legs 15 on its sides, the combination with the sheets forming said water-legs of a mud-ring fitting between the sheets, a grate to carry a fuel bed at substantially the level of the upper surface of the ring, said ring having a cavity 20 extending lengthwise and below the fuel bed, and ducts extending from its upper surface to the cavity, and means securing the sheets to the mud-ring, there being normally closed wash-out openings from the cavity.

2. In apparatus of the class described comprising a fire-box with the usual water-legs on its sides, the combination with the sheets forming said water-legs of a mud-ring 30 fitting between the sheets, said ring having a cavity extending lengthwise and ducts extending from the cavity to the upper surface of the ring, and means securing the sheets to the mud-ring, the said cavity being below the 35 points exposed to the direct heat in the firebox, there being normally closed wash-out openings from the cavity.

3. In apparatus of the class described comprising a fire-box with the usual water-legs 40 on its sides, the combination with the sheets forming said water-legs of a mud-ring fitting between the sheets, said mud-ring having a hollow portion extending downward below the lower edges of the sheets 45 around the four sides, there being ducts distributed along the mud-ring extending from the said hollow to the upper surface of the ring, and means securing the sheets to the mud-ring, there being normally closed wash-out openings from the hollow.

4. In apparatus of the class described, a firebox with the usual boiler water leg at its side, the combination therewith of a mud ring fitting between the inner and outer sheets 55 of the water leg, said ring having a hollow chamber below its upper surface, and ducts extending from points on its upper surface, in close proximity to said inner sheet, to said chamber, there being normally closed wash-out outlets leading from the interior of said chamber through the wall thereof to the exterior of the boiler.

5. An integral mud ring structure having a solid upper part extending substantially 60 throughout the entire length of the ring and

to which firebox sheets may be attached, a hollow part below said part and extending substantially throughout the entire length of the ring, there being ducts through said solid part leading to said hollow part through which ducts sludge from above said ring may settle into said hollow part, and there being normally closed washout outlets in portions of the ring below said upper part leading from said hollow part to the exterior of the ring.

6. A mud ring having a substantially solid portion adapted to receive firebox sheet securing means, a hollow portion below said solid portion, there being a series of ducts through said solid portion to said hollow portion through which ducts sludge may drain freely from between said sheets to said hollow portion, said hollow portion having at least one normally closed outlet below said ducts for washing out sludge gathered in said hollow portion.

7. In a mud ring, a hollow chamber, there being ducts leading from the upper surface of the ring, in close proximity to the inner side thereof, to said chamber and through which ducts sludge tending to accumulate on said upper surface adjacent to said inner side may drain to said chamber, there being normally closed washout outlets in the lower wall of said chamber.

8. In a mud ring, a hollow chamber, and ducts leading from the upper surface of the ring to said chamber and through which ducts sludge deposited on said upper surface may drain into said chamber, said chamber being provided with normally closed washout outlets discharging below the upper part of the mud ring.
